(57) **CLAIM**

The ornamental design for a climbing frame as shown and described.

DESCRIPTION

FIG. 1 is a front, left side isometric view of our new design for a climbing frame.

FIG. 2 is a top side plan view of FIG. 1.

FIG. 3 is a bottom side plan view of FIG. 1.

FIG. 4 is a front side elevation view of FIG. 1.

FIG. 5 is a back side elevation view of FIG. 1.

FIG. 6 is a right side elevation view of FIG. 1; and,

FIG. 7 is a left side elevation view of FIG. 1.

The features shown in broken lines in the drawing depict environmental subject matter only, and form no part of the claimed design.

1 Claim, 7 Drawing Sheets
